UNITED STATES PATENT OFFICE.

CHARLES B. HARRIS, OF NEW YORK, N. Y.

ICE MAKING AND CUTTING MACHINE.

SPECIFICATION forming part of Letters Patent No. 638,577, dated December 5, 1899.

Application filed April 12, 1899. Serial No. 712,802. (No model.)

To all whom it may concern:

Be it known that I, CHARLES B. HARRIS, a citizen of the United States, and a resident of New York, in the county of New York and State of New York, have invented certain new and useful Improvements in Ice Making and Cutting Machines, of which the following is a specification.

The object of this invention is the production of a machine by means of which clear ice in small particles of various sizes can be produced for regelation.

The means heretofore used to prepare ice for regelation has produced regelated ice of a cloudy appearance by virtue of the entrapping of a considerable number of air-bubbles between the particles of ice, resulting to a great extent from the ice being cut in particles of too small dimensions and also by reason of being exposed to the air while being broken or cut in small particles.

The apparatus which constitutes this invention can produce ice in particles of various sizes, cut or broken under water, thereby avoiding the excessive entrapping of air, and the product when regelated producing clear ice.

To these ends my invention consists of a revolving freezing-cylinder, for the accumulation of ice, and adjustable cutting-tools, operating under water, to detach the ice in suitable condition for regelation.

Referring to the drawings, in which like parts are designated by similar letters of reference, Figure 1 shows an elevation of my invention, partly in section on the line C' D''. Fig. 2 represents an end view with a fragmentary section, taken on the line E' F'. Fig. 3 is a partial elevation of the frame of the machine with conveyer and extended trough. Fig. 4 shows a plan of Fig. 3. Fig. 5 represents a sectional elevation of the device, taken on the line G' H'. Fig. 6 shows a fragmentary plan. Figs. 7, 8, 9, and 10 represent details of the cutting devices.

Referring to the drawings, the freezing-cylinder is shown at E, to which are secured the long hollow journals d and d', which turn in the combined bearings and stuffing-boxes d'' and d'', the latter being a part of and cast with the trough F. Glands d''' d'' are fitted to the stuffing-boxes to prevent the leakage of water

from the trough F. To the ends of the hollow journals d and d' are fitted glands d'' d''', which fit the stuffing-boxes d'', to secure tight joints between the pipes b and i and the hollow journals d and d', preventing the escape of the refrigerant.

It will be noticed that the trough F constitutes and forms part of the frame or housing for the machine. The side f'' is concaved and concentric with the freezing-cylinder E, and it continues under the said cylinder until it runs into the plane surface f''. At f'' and f''' straight vertical ends are shown. A straight vertical leg is shown at f'', which joins with the secondary trough f'' for the conveyer R. At the junction of the leg f'' and trough f'' a concaved plate f'' is secured by bolts f'', the said plate extending between the ends f'' and f'''.

An inspection of Fig. 5 will clearly show that the sides and ends of the trough F are brought above the level of the plate f'', which in turn is situated above the cutting-tools q and q', allowing, in the first place, the cutting-tools to operate under water and preventing the water contained in the trough F from overflow in the secondary trough f''.

To properly carry off the particles of ice, the secondary trough f'' is extended by bolting to the side f'' the extended trough R', as shown in Figs. 3 and 4. This trough R' contains the opening r for delivering the particles of ice. A conveyer R revolves in the trough f'' and its extension R', the shaft v of said conveyer turning in the journal-boxes v', being driven by any suitable source of power.

At P'' is shown a shaft with blades P'' P'', &c., turning in journal-boxes P'', a pulley P'' being secured to the shaft and driven by any suitable power. The object of the blades P'' P'', &c., is to sweep the particles of ice, after being cut from the freezing-cylinder E, up the curved plate f'' and into the trough f''.

At h is shown a horizontal pipe leading from the pipe g, with its valve g', by means of which the trough is fed with water, the pipe h being perforated with numerous holes on its bottom side. An outlet b'' is provided at the bottom of the trough F to drain and clean the same.

To the hollow journal d' is fixed the spur-gear G, which can be driven by any source of

power. The said gear communicates its motion to the freezing-cylinder E.

The bevel-gears H and H'', shaft J, and bevel-gears K and K'' communicate motion 5 to the shaft M, which in turn actuates at the proper intervals the knives q and q'.

The gearing is proportioned to rotate the freezing-cylinder E one revolution while the shaft M makes one-half of a turn.

10 The shaft M carries grooved cams M'', by which the cutting-tools are kept in a proper position to cut ice from the freezing-cylinder E during one revolution of the said cylinder and are then moved out of position from said cylinder for the next revolution, to allow the accumulation of ice, and so on alternately. To secure these ends, one half of the groove in each cam M'' is cylindrical and concentric with the shaft M, as shown at a³ b³ c³, while 15 the other half of the groove, a³ e³ c³, is somewhat flattened and closer to the center of the shaft M. The forked ends n² of the spindle N'' carry pins n³, with rollers n⁴, which fit the said grooves, and when the portion a³ b³ c³ 20 comes in gear with the rollers n⁴ the position of the spindle N'', with the set of knives, is not disturbed, and the ice is cut from the cylinder; but when the portion a³ e³ c³ comes in contact with the rollers n⁴ the spindle N'', and consequently 25 its set of knives, is drawn toward the center of the shaft M and away from the cylinder E. The positions of the knives are thus alternately against and away from the freezing-cylinder. The distance between the 30 ends of the spindles N and N'' is adjusted by the turnbuckle n⁵ to gage the ice cut from the freezing-cylinder at the proper thickness.

The grooved cams M'' are placed on the shaft M so that one set of knives, as in the 40 holder Q, are against the cylinder, while the knives next adjacent, as in the holder Q'', are away from the same, by which alternate sets of knives cut bands of ice off the cylinder, while the remaining sets of knives allow the 45 revolving cylinder to collect ice.

The knife-holders Q Q'' are substantial castings, with the vertical pockets q⁴ and feet q⁵ reciprocating in the guides V V. Lugs q⁷ are provided for securing spindles N, the said 50 lugs being tied to the vertical walls of the pockets by the ribs q⁹. Openings q¹⁰ are left to insert nuts n⁶ for securing the spindles N.

The knives are held in upright positions in the cavities q⁴, where adjusting-pieces q⁵ assist to properly locate and secure them with the screws q⁶. This disposition of the knives prevents bending when in use and avoids the tremor consequent to cutting-tools when not properly secured.

60 Stuffing-boxes f' are cast with the legs f² of the trough F, through which the spindles N reciprocate.

The disposition of each set of knives is novel, the knives in each set being alternately placed on different levels with respect to the center of the cylinder, as shown at q and q', so that the upper level of knives cuts

the first strip of ice and the lower level cuts the remainder, the edges of the knives overlapping to thoroughly clean the cylinder of 70 ice. The overlapping edges of the knives are seen at t² t² and t³ t³. By this disposition of the knives plenty of clearance is given to the cutting edges, and the liability of their becoming clogged with ice and breaking is 75 avoided.

It will be seen that the actions of the knives with respect to the revolving cylinder are automatic in operation.

In Fig. 10 I show a modified form of operating the knives in which they are continuously held against the revolving cylinder. The construction is cheaper, and the shaft M, with the cams M'', is dispensed with. The spindle N³ in this modified form is made in 85 one piece, with a screw-thread s⁴ working through the threaded lug s⁵. The hand-wheel S³ adjusts the position of the knives with respect to the revolving cylinder E. The end of the spindle N³ is turned down and fitted 90 with two collars n⁷ and n⁸, which work easily against the lug q¹², allowing the spindle N³ to turn and move the knife-holder.

To operate my device, ammonia or some other refrigerant enters the pipe b, on its passage to the freezing-cylinder E, through the hollow journal d. The said refrigerant expands and produces its refrigerating effect on water adhering to cylinder E. The refrigerant, after expanding in the freezing-cylinder E, leaves the same through the hollow journal d' and piping i. The ice which is frozen on the cylinder is cut from the same by the knives q q' and deposited on the curved plate f⁸, where the blades P'' P'', &c., sweep 105 it into the trough f⁶ for the conveyer R to carry it to the opening r in the extended trough R', when other machinery is brought into action to regulate the particles of ice.

Having fully described my invention, I desire to secure by United States Letters Patent and claim—

1. An ice making and cutting machine comprising; a revolving hollow freezing-cylinder; long hollow bearings for said cylinder, with 115 stuffing-boxes secured thereto; a cleanable water-trough with ends constituting combined bearings and stuffing-boxes; a perforated supply-pipe with valve; knife-holders with knives securely held in vertical pockets 120 with adjusting plates and screws; a cam-shaft with grooved cams, one half of the said grooves being concentric with center of cam-shaft, and other half flattened and closer to center of said shaft; spindles with forked ends and 125 rollers, transmitting movements from grooved cams to knife-holders; turnbuckles to vary the lengths of the spindles with forked ends; a gear-wheel secured to hollow bearing of revolving cylinder; bevel-gears with shaft and 130 pillow-blocks to transmit motion from revolving cylinder to cam-shaft; revolving blades and conveyer all as substantially described.

2. An ice making and cutting machine comprising; a hollow revolving freezing-cylinder; long hollow bearings for said cylinder, with stuffing-boxes secured thereto; a cleanable water-trough with ends constituting combined bearings and stuffing-boxes, and a front wall containing stuffing-boxes for spindles of knife-holders, the height of the trough arranged to allow ice to be cut from revolving cylinder under water; a perforated supply-pipe with valve to allow water to flow on top of freezing-cylinder; knife-holders with knives securely held in vertical pockets with adjusting plates and screws, and arranged to cut particles of ice in bands from the revolving cylinder below the surface of the water; a cam-shaft with grooved cams, one half of said grooves being concentric with center of cam-shaft, and the other half flattened and closer to said shaft; spindles with forked ends and rollers, operating through the stuffing-boxes of front wall of trough, and transmitting movements from the grooved cams to knife-holders turnbuckles to vary the lengths of the spindles with forked ends; a gear-wheel secured to the hollow bearing of revolving cylinder; bevel-gears with shaft and pillow-blocks to transmit motion from revolving cyl-inder to cam-shaft; a concaved plate bolted to trough, revolving blades, and a conveyer to carry the particles of ice cut from the freezing-cylinder, all as substantially described. 30
3. An ice making and cutting machine comprising; revolving cylinder E, with journals d and d', stuffing-boxes d⁴ d⁴', glands d⁵ and piping b, i, trough F, with stuffing-boxes d⁷ d², glands d³, d⁸; supply-piping h and g, and outlet-pipe b²; spur-gear G; bevel-wheels H, H' K', K''; shaft J, pillow-blocks J'', J³; cams M', cam-shaft M; spindles N, N'', with forked ends n², pins n³ and rollers n⁴; turnbuckles n⁵; stuffing-boxes f'; knife-holders Q, Q'', knives q, q', plates q⁵ and screws q⁶; conveyer R, secondary trough f⁶, journal-boxes v', and extended trough R'; revolving blades P'', &c., with shaft P⁴, and pillow-blocks P⁶ cast with the trough, all as substantially described. 35 40 45 50

Signed at New York, in the county of New York and State of New York, this 7th day of April, A. D. 1899.
